Henry J. Lucke

UNITED STATES PATENT OFFICE.

EVERETT W. SWARTWOUT, OF WHITE PLAINS, NEW YORK.

LAY SHAFT.

Application filed August 23, 1916. Serial No. 116,432.

To all whom it may concern:

Be it known that I, EVERETT W. SWARTWOUT, a citizen of the United States, and residing at White Plains, county of Westchester, State of New York, have invented certain new and useful Improvements in Lay Shafts, of which the following is a specification.

The invention relates to lay shafts.

10 More particularly, the invention relates to improvements in lay shafts and valve controlling means operated by the same constructed and arranged to be unaffected by expansion and contraction of the engine due to temperature variations. The invention is also directed to improved simplified means for operating the lay shaft and the valve controlling means operated by the same.

15 In the hereinafter described specific embodiment of the invention, I have set forth a preferred form of the invention applicable particularly to steam engines, although it will be understood that the invention is capable of general use under conditions of expansion and contraction due to temperature or other variations for rotating or oscillating a member and provided with mounting means therefor for rendering such variations ineffectual on the operation of such member.

20 In such preferred form of the invention as applied to steam engines, the lay shaft is mounted in close proximity to the steam engine as by means of suitable mounting means directly on the casing of the engine and the 25 lay shaft is oscillated preferably by means of a cam carried directly by the engine shaft and effecting the oscillation of the lay shaft through improved driving means. Such arrangement embodies advantages in simplicity of construction and operation of directly actuated cam shafts and avoids the use of beveled or mitre gearing and special governing devices, which have proven to be highly complicated and expensive and of 30 practical limitation.

Further features and objects of my invention will be more fully understood from the following description and the accompanying drawings, in which

35 Fig. 1 is a perspective view showing an improved type of uniflow engine provided with a lay shaft and operating means embodying my invention;

40 Fig. 2 is a detail view of the bearings of the lay shaft shown in Fig. 1 on an enlarged scale;

Fig. 3 is a detail perspective view;

Fig. 4 is a detail side elevation showing a modification of universal connection; and Fig. 5 is a detail view of the turn buckle 60 of the bell crank indicated in Fig. 1.

Referring to Fig. 1, the casing 1 of the uniflow engine is provided with the usual bonnets 2 enclosing the poppet valves controlling the inflow of the engine. The studs 65 or valve shafts of the indicated two poppet valves are designated 3, 4, respectively. The frame 5 of the engine is of any approved type. The engine shaft is indicated at 6.

70 In the preferred form of the invention illustrated in the drawings, the eccentric 7 is shown positioned directly on the engine shaft 6. The relation between eccentric 7 and shaft 6 will be varied by any approved means, as will be understood by those skilled 75 in the art.

75 The eccentric rod 8 is pivoted to the arm 9 of bell crank 10, pivoted at 11 on a carrier arm, bracket or the like, and the arm 12 of bell crank 10 is connected with the link 16 80 by means of a universal connection such as the pivot lug 13 extending through the opening in the stud 14 carried within the fork 15 of the link 16. The link 16 is provided at its opposite end with a similar arrangement 85 comprising the fork 17 carrying the stud 18 provided with a suitable opening receiving the headed pivot lug 19 of the oscillating link 20, connected to the lay shaft 21. Figure 3 shows the links 16 and 20 and the connecting parts on a somewhat enlarged scale. The lay shaft 21 is shown mounted on the forward bracket 22 and the rearward bracket 23. Preferably, the lay shaft 21 is 90 of polygonal cross section. The lay shaft 95 21 controls the valve shaft 3 by means of the arm 24, link 25, and arm 26, the last named being connected directly to the valve shaft 3. Similarly, the lay shaft 21 controls the valve shaft 4 by means of the arm 27, link 100 28 and arm 29. As indicated, the valves are adjusted relatively to control the proper instants of entry of the steam through the respective entry ports controlled by the same.

105 Referring to Figs. 2 and 4 the forward mounting comprises preferably the collar 30 having a circular exterior face 31 and an inner polygonal face 32 conforming to the outer face of lay shaft 21 but of slightly larger cross-section to permit movement 110 relatively between the bracket 22 and the lay shaft 21 in the direction of length of the

lay shaft 21, incident to expansion or contraction upon operation of the engine.

The collar 30 is provided with the seat 33 receiving the arm 27 and on the opposite face is provided with the positioning plate 34 having the adjusting screws 35. Preferably, the arm 24 is mounted on the lay shaft 21 by means of similar collar 30 and retaining and adjusting plate 34, combined with 10 the bracket 23, said plate 34 of the arm 24 retaining the lay shaft 21 against longitudinal movement relative to the bracket 23 by making a close fit with the lay shaft 21 or by means of a set screw, as generally indicated at 39 in Fig. 2, or in any other approved manner. Accordingly, upon expansion and contraction of the casing 1 and therewith of the bracket 22 relative to the lay shaft 21, the arm 27 will be maintained 20 continuously in proper relationship to the arm 29 of the valve shaft 4 and in proper relation to the valve shaft 3 and its operating parts.

The adjustment of the extent of throw 25 of the valve shafts, i. e., extent of oscillation of the lay shaft 21, may be modified by proper adjustment of the arm 9 of bell crank 10, as by means of the adjusting nut 36 having a right hand and left hand screw 30 threaded connection, see Fig. 5 with the parts of said arms 9.

A universal connection of suitable construction such as the ball and socket type 35 may be substituted for the specific connection shown. In Fig. 4 I have shown the ball and socket joint 40 connecting one end of the link 16 with the arm 12 of the bell crank 10, and the ball and socket joint 41 connecting the opposite end of the link 16 40 with the arm 20 of the lay shaft 21.

Accordingly, it will be noted that the invention affords the maintenance of the desired relative operations of the valve regulating ports irrespective of expansion and contraction due to temperature changes.

The invention is also characterized by simplicity of construction and assembly, decrease in space required, positiveness in action and simplicity in adjustment.

50 I claim:

1. The combination with an apparatus constructed to be operated by a medium at a temperature different from atmospheric temperature and having a plurality of cor-

responding ports and valves controlling 55 said ports, of means for simultaneously controlling said valves to uniformly determined extents independently of any variation in temperature effected by the medium in the operation of said apparatus, said controlling means comprising an oscillatable 60 relatively long member having a portion of angular contour, an element fixedly mounted on said member and controlling one of said valves and another member having an 65 opening of similar angular contour but of relatively larger cross section and receiving the angular portion of said member and controlling another of said valves.

2. In an engine valve gear, the combination 70 of a rocker oscillating on an axis at a right angle to the engine cylinder axis, a lay shaft parallel to the cylinder axis, and connecting means between the rocker and lay shaft, to operate the latter, said means including universal joints permitting variations in relative position between the shaft and rocker, the lay shaft being movable longitudinally relative to the cylinder, whereby expansion of the cylinder will not 80 vary the angular relation of the lay shaft and the rocker.

3. The combination with an engine cylinder 85 and its valves, of a valve operating lay shaft extending beside the cylinder and parallel thereto, a lever vibrating on an axis at an angle to the axis of said shaft, and connected to the lay shaft, and means to operate the lever, the lay shaft being movable longitudinally relative to the cylinder, 90 whereby expansion of the cylinder will not vary the angular relation of the lay shaft and the lever.

4. In an engine valve-gear, the combination 95 with an engine cylinder, its valves and crank shaft, of means actuated by the crank shaft to produce reciprocating movements in a plane parallel to the axis of the engine cylinder and means to convert said movements into movements at a right angle to said axis and transmit same to the valves, the last mentioned means including devices 100 to permit variation of the position of the valves without varying the angular relation of the movements so converted.

In testimony whereof I have signed this specification.

EVERETT W. SWARTWOUT.
